PAPER BASKET AND CONTAINER

Philip K. Madan, Mount Vernon, N. Y., assignor
to Perfection Products Co., Inc., Mount Vernon,
N. Y., a corporation of New York

Application November 10, 1943, Serial No. 509,654

9 Claims. (Cl. 229—6)

This invention relates to what are commonly referred to as waste paper baskets, and similar containers composed entirely of paper and paper board. More particularly, the invention relates to a simple and economical method of producing strong and durable containers or receptacles of the kind defined, and particularly in the provision of an upper unitary rim or retaining ring structure employed for supporting and maintaining the walls of the receptacle at the open end thereof in position. The novel features of the invention will be best understood from the following description when taken together with the accompanying drawing, in which certain embodiments of the invention are disclosed, and in which the separate parts are designated by suitable reference characters in each of the views; and in which:

Fig. 1 is a diagrammatic side view of a basket or receptacle made according to the invention, omitting the details of the facing materials employed.

Fig. 2 is a section on the line 2—2 of Fig. 1, on an enlarged scale and showing the details of construction of the wall parts of the basket, particularly with respect to the facing materials thereof.

Fig. 3 is a section on the line 3—3 of Fig. 1, also including the details of the facing materials employed.

Fig. 4 is a section on the line 4—4 of Fig. 1, to illustrate the overlapping ends of the outer facing sheets employed, but omitting the inner facing of the wall members of the container; and

Fig. 5 is a plan view of one of a number of unitary rings or frame portions employed in reinforcing and supporting upper free edges of the basket walls in position.

In the art of producing receptacles, such for example as waste paper baskets, these receptacles have been composed of metal and have been made of fiber board and similar materials, but in production of baskets of this kind, considerable expense has been devoted to the cost of production, which has resulted in a relatively high selling price, even in baskets of this type and kind composed of paper or fibrous material.

It is the object of my invention to produce a very economical product of this kind and yet one which will possess the required strength and durability, so as to provide a reasonably long use, and at the same time, present an attractive, neat and finished appearance. Furthermore, by reason of the manner of constructing the top and bottom reinforcements and supporting members

of the walls of the basket or receptacle, it is possible to minimize the amount of scrap in the cardboard, paper board or the like, mounted by utilizing the different sizes of the cut out portions in the construction of receptacles of different sizes which from the standpoint of packing and shipment can be telescoped one within the other in a single size, or nested one within the other in the sale and/or shipment of groups of baskets of different sizes.

While baskets of the type and kind under consideration are designed primarily for the use in the home, they will also have useful purposes in offices and places of business, or anywhere where normal use of waste paper baskets is desirable. Furthermore, by utilizing facings of waterproof material, the uses of these baskets may be extended beyond the conventional use as a receptacle for paper alone.

20 Insofar as the ornamentation of the basket is concerned, this can be accomplished by the facing materials employed on the various wall portions of the basket, including the reinforcing and retaining ring or rim at the upper open edge thereof. In that different facing sheets are employed on the several parts, contrasting characterizations can be employed, or all of these facing sheets may have similar characteristics.

Characterization is omitted from Fig. 1 of the drawing, in that it is understood that this phase of the product would have nothing to do with the invention.

The basket or receptacle is constructed from a body 10, composed of eight angularly disposed walls forming an octagon cross sectional contour. This body is formed from a single sheet of material, scored and folded in such manner as to form eight panels 11, having a permanent facing sheet 12 on the inner surface thereof applied in the production of the sheet from which the paneled body 10 is formed. The panels 11 are tapered to the lower end 13 of the body 10, so that this end is of smaller diameter than the upper end 14, as will clearly appear from a consideration of Fig. 1 of the drawing.

The ends of the scored and folded sheet employed for forming the body 10 abut, as seen at 15, note Fig. 4, in forming one of the corners of the eight sided body.

50 The bottom of the basket or receptacle is formed from two or more discs 16, having eight angularly disposed boundary walls to fit snugly within the panels or walls 11. At 17 is shown two or more unitary octagon rings which are 55 adapted to be arranged upon the outer surfaces

of the panels or walls 11 at the open end 12 thereof, in supporting these walls in the assembled relationship. A lower facing sheet 18 is mounted upon and glued or otherwise secured to the lowermost disc 16, and to the lower edge or end 13 of the walls or panels 11, and has flange portions 19 extending onto the outer surfaces of the panels 11 and secured thereto.

A finishing or facing strip 20 is also arranged upon the upper open end portion 14 of the walls 11, and upon the rings 17, this strip having flange portions 21 extending onto and secured to the inner surfaces of the walls 11 or the facing sheets 12 thereon, as well as flange portions 22, which extend onto the lower surface of the lowermost member 17 and secured thereto. The facing or finishing sheet 20 being secured to the other parts over which the same is arranged.

The body portion or the walls or panels 11 are covered with an outer facing 23, which is preferably composed of two parts having overlapping edges, as at 24, at opposed corners or intersections between two pair of panels or walls 11. The illustration in Fig. 4 of the drawing is exaggerated for sake of clarity, it being understood that the facing sheets are of thin material, and will not present any visible irregularity or bulge at these corners of the basket.

By using two sheets in constructing the facing 23, assemblage of this facing to the walls of the basket is simplified. The facing being glued in position. Upper edges of the facing 23 or the separate parts thereof include outwardly extending flange portions 25, note Fig. 2, which are arranged upon and secured to the reinforcing ring or the flange portion 22 of the facing on this ring and the upper portion of the wall structure of the basket. It will also be noted from a consideration of Fig. 3, that the lower edge portion 26 of the facing 23 is arranged over and secured to the flange portions 19 on the bottom facing 18.

In blanking the reinforcing rings, such as 17, from sheets of cardboard, fiber board or other material employed in constructing the basket, the inner blanked out portions in the form of octagon discs can be utilized in forming the bottom wall disc 16 of the basket, but not necessarily the same basket to which the rings are attached, depending entirely upon the taper desired in the resulting wall structure of the basket. Several rings of different sizes may be blanked out from a single sheet, and these different sized unitary rings can be employed in constructing baskets or receptacles of different sizes, which will nest one within the other. In this method of procedure, a minimum amount of cardboard will be wasted. This results in a material saving in the cost of producing the product.

The solid or unitary ring like structure of the reinforcing bead or flange at the top of the basket gives outstanding strength to the resulting basket. In the same manner, the octagon discs provides a strong and durable bottom for the basket, and while three of these discs are shown in the present construction, and two rings employed at the top of the basket, single discs and rings can be employed, or the members of these rings or discs may be varied to suit different uses.

By shifting the position of one ring to rest with an associate ring, when two rings are employed to reinforce the top of the basket, greater strength will be provided in changing whatever graining there may prevail in the paper or cardboard from which these rings are constructed.

In the use of baskets of the kind under consideration, the strain upon the walls of the basket is for the most part outward, particularly in any tendency to over fill the basket, and these outward pressures are taken up and checked by the unitary reinforcing ring structure at the top of the basket. Of course, the baskets are not intended for excessive packing, but as constructed, are made to resist pressures of this kind that may be administered in careless use of the baskets.

From a standpoint of transportation and handling, the entire basket construction is strong and durable, and by reason of the tapered contour in the wall structure of the body of the basket, in addition to providing strength in the basket by virtue of the angularly disposed wall, a neat and attractive basket is produced. Furthermore, this tapered structure lends itself to close packing of baskets of a common size to minimize the shipping space of many baskets, and furthermore, this structure lends itself to the complete nesting of a plurality of baskets of different sizes one within the other, so that for example, a group of three different size baskets may be sold as a unit, and in such instances, the two smaller baskets will be contained entirely within the dimensions of the outer larger baskets.

It will be apparent that from the standpoint of the wall structure of the body of the basket as a whole, comprising the foldable related panels tapering to the lower end in the manner described, produces a strong basket body resisting outward pressures. The bottom members support and maintain the walls or panels in their proper relationship to each other in sustaining the basket against inward collapse, and the rings at the upper end of the basket support the walls in proper position and retain these walls against outward spreading.

When the baskets or containers are likely to be subjected to moisture, the paper facing 12 and the facing 16 on the uppermost wall 16, will be waterproofed. On the other hand, facings having waterproofed characteristics may be used on these surfaces, as well as all of the surfaces of the basket or container.

The present illustration and manner of constructing the product is to illustrate one adaptation of the invention, and it will be understood that shapes and relative sizes of the various parts may be modified to suit the uses for which the product is intended. It will also be understood that in the construction of the bottom of the basket, as well as the reinforcing ring flange at the upper edge thereof, the separate members or sheets may be secured together by gluing or in any desired manner.

Having fully described my invention, what I claim as new and desire to secure by Letters Patent is:

1. A basket of the class described, comprising a tubular body formed from angularly disposed cardboard or paper board side walls, said walls converging to the lower end of the body, two facing sheets secured to outer surfaces of said walls and having overlapping edges at intersections between adjacent walls, a bottom wall having a peripheral contour conforming to the cross sectional contour of the walls of said body and fitting within the body at the lower end thereof, a facing sheet secured to the bottom wall and to the lower edges and outer surfaces of said angularly disposed walls in supporting the bottom walls in position, a solid ring arranged upon outer sur-

faces of said angular walls at the upper end portion thereof and snugly conforming to the cross sectional contour of said wall, said ring providing an outwardly projecting flange on the upper edge of the basket and being flush with said edge, and means securing said ring like flange to the upper edge portion of the angularly disposed walls of the basket body.

2. A basket of the class described, comprising a tubular body formed from angularly disposed cardboard or paper board side walls, said walls converging to the lower end of the body, two facing sheets secured to outer surfaces of said walls and having overlapping edges at intersections between adjacent walls, a bottom wall having a peripheral contour conforming to the cross sectional contour of the walls of said body and fitting within the body at the lower end thereof, a facing sheet secured to the bottom wall and to the lower edges and outer surfaces of said angularly disposed walls in supporting the bottom walls in position, a solid ring arranged upon outer surfaces of said angular walls at the upper end portion thereof and snugly conforming to the cross sectional contour of said wall, said ring providing an outwardly projecting flange on the upper edge of the basket and being flush with said edge, means securing said ring like flange to the upper edge portion of the angularly disposed walls of the basket body, said last named means comprising a paper strip completely enveloping the flange, and overlying the upper edge and inner surface of the angularly disposed walls of said body.

3. A basket of the class described, comprising a tubular body formed from angularly disposed cardboard or paper board side walls, said walls converging to the lower end of the body, two facing sheets secured to outer surfaces of said walls and having overlapping edges at intersections between adjacent walls, a bottom wall having a peripheral contour conforming to the cross sectional contour of the walls of said body and fitting within the body at the lower end thereof, a facing sheet secured to the bottom wall and to the lower edges and outer surfaces of said angularly disposed walls in supporting the bottom walls in position, a solid ring arranged upon outer surfaces of said angular walls at the upper end portion thereof and snugly conforming to the cross sectional contour of said wall, said ring providing an outwardly projecting flange on the upper edge of the basket and being flush with said edge, means securing said ring like flange to the upper edge portion of the angularly disposed walls of the basket body, said last named means comprising a paper strip completely enveloping the flange and overlying the upper edge and inner surface of the angularly disposed walls of said body, and the outer facing sheets of said body having outwardly extending flanges secured to the lower surface of said ring like flange.

4. A basket of the class described, comprising a tubular body formed from angularly disposed cardboard or paper board side walls, said walls converging to the lower end of the body, two facing sheets secured to outer surfaces of said walls and having overlapping edges at intersections between adjacent walls, a bottom wall having a peripheral contour conforming to the cross sectional contour of the walls of said body and fitting within the body at the lower end thereof, a facing sheet secured to the bottom wall and to the lower edges and outer surfaces of said angularly disposed walls in supporting the bottom walls in position, a solid ring arranged upon outer surfaces of said angular

walls at the upper end portion thereof and snugly conforming to the cross sectional contour of said wall, said ring providing an outwardly projecting flange on the upper edge of the basket and being flush with said edge, means securing said ring like flange to the upper edge portion of the angularly disposed walls of the basket body, said last named means comprising a paper strip completely enveloping the flange and overlying the upper edge and inner surface of the angularly disposed walls of said body, the outer facing sheets of said body having outwardly extending flanges secured to the lower surface of said ring like flange, and said ring like flange being composed of similar ring members secured together.

5. A basket of the class described, comprising a tubular body formed from angularly disposed cardboard or paper board side walls, said walls converging to the lower end of the body, two facing sheets secured to outer surfaces of said walls and having overlapping edges at intersections between adjacent walls, a bottom wall having a peripheral contour conforming to the cross sectional contour of the walls of said body and fitting within the body at the lower end thereof, a facing sheet secured to the bottom wall and to the lower edges and outer surfaces of said angularly disposed walls in supporting the bottom walls in position, a solid ring arranged upon outer surfaces of said angular walls at the upper end portion thereof and snugly conforming to the cross sectional contour of said wall, said ring providing an outwardly projecting flange on the upper edge of the basket and being flush with said edge, means securing said ring like flange to the upper edge portion of the angularly disposed walls of the basket body, said last named means comprising a paper strip completely enveloping the flange and overlying the upper edge and inner surface of the angularly disposed walls of said body, the outer facing sheets of said body having outwardly extending flanges secured to the lower surface of said ring like flange, said ring like flange being composed of similar ring members secured together, and said bottom wall being composed of a plurality of members secured together.

6. A basket of the class described, comprising a tubular body formed from angularly disposed cardboard or paper board side walls, said walls converging to the lower end of the body, two facing sheets secured to outer surfaces of said walls and having overlapping edges at intersections between adjacent walls, a bottom wall having a peripheral contour conforming to the cross sectional contour of the walls of said body and fitting within the body at the lower end thereof, a facing sheet secured to the bottom wall and to the lower edges and outer surfaces of said angularly disposed walls in supporting the bottom walls in position, a solid ring arranged upon outer surfaces of said angular walls at the upper end portion thereof and snugly conforming to the cross sectional contour of said wall, said ring providing an outwardly projecting flange on the upper edge of the basket and being flush with said edge, means securing said ring like flange to the upper edge portion of the angularly disposed walls of the basket body, said last named means comprising a paper strip completely enveloping the flange and overlying the upper edge and inner surface of the angularly disposed walls of said body, the outer facing sheets of said body having outwardly extending flanges secured to the lower surface of said ring like flange, said ring like flange being composed of similar ring members secured to-

gether, said bottom wall being composed of a plurality of members secured together, an inner facing sheet on the walls of said body and the surface of the bottom wall, and said last named sheets being waterproofed.

7. In a container having a body portion the walls of which, in cross section, are composed of paper board and arranged at an angle greater than ninety degrees to each other, a unitary member secured to and completely enveloping all of the walls of said body at the open end thereof, and flush with the edges of said walls at said end for reinforcing and supporting said walls at said open end of the body, said member comprising a pair of horizontally flat paper board rings forming an outwardly extending flange at the upper edge of said container, and said rings being secured to the container by a strip enveloping the outer surfaces of the rings and extending over the upper edge of said walls of the container and onto the inner surfaces thereof.

8. In a container having a body portion the walls of which, in cross section, are composed of paper board and arranged at an angle greater than ninety degrees to each other, a unitary member secured to and completely enveloping all of the walls of said body at the open end thereof,

5 and flush with the edges of said walls at said end for reinforcing and supporting said walls at said open end of the body, said member comprising a pair of horizontally flat paper board rings forming an outwardly extending flange at the upper edge of said container, said rings being secured to the container by a strip enveloping outer surfaces of the rings and extending over the upper edge of said walls of the container and onto the inner surfaces thereof, and an outer facing on the walls of said container including flange portions arranged upon and secured to the lower surface of said ring like flange.

10 15 20 25 9. The combination with a paper board container of octagon cross sectional form of a unitary octagon and horizontal flat ring, said ring having wide upper and lower surfaces and narrow inner and outer edges, the inner edge of said ring fitting snugly upon the walls of said container with the upper surface of said ring flush with the upper edge of said walls, said ring forming an outwardly projecting reinforcing flange at said edge of the container, and means comprising facing sheets secured to the container and said ring for supporting the ring on the walls of the container with said walls in firm engagement with said ring.

PHILIP K. MADAN.
